UNITED STATES PATENT OFFICE.

THOMAS RYAN, OF BUXTON, ENGLAND.

ECONOMIZER FOR LIMEKILNS.

SPECIFICATION forming part of Letters Patent No. 727,845, dated May 12, 1903.

Application filed December 6, 1902. Serial No. 134,186. (No model.)

To all whom it may concern:

Be it known that I, THOMAS RYAN, a subject of the King of Great Britain and Ireland, residing at The Woodlands, Buxton, in the county of Derby, England, have invented a new and useful Improvement in Economizers for Limekilns, of which the following is a specification.

My invention relates to economizers for limekilns, and the following is a full, clear, and exact description of my invention, reference being had to the accompanying drawings, in which—

Figure 1 is an elevation. Fig. 2 is a sectional plan as on line *xx* of Fig. 4. Fig. 3 is a section as on line *yy* of Fig. 2. Fig. 4 is a similar view to Fig. 3, but taken as at right angles thereto.

Like numerals refer to corresponding parts in all the figures.

My invention is applicable to the type of limekiln known as "open-running kiln." The line A B in Figs. 1, 3, and 4 indicates the top level of such a kiln, the construction of which is well known and forms no part of my invention. Above the top of the kiln I build two arches 1 2, with a space or slot 3 between them. The outside ends 4 of these arches are provided with stoking- orifices 5, normally closed by doors 6, and through these doors fuel is fed at suitable intervals. A short distance from the outside ends 5 of the arches I affix a metal sheath 7, and the space 8 between them serves as an air-heating chamber, which is fed with air through air-supply pipes 9 from any suitable source. The air from chambers 8 enters the economizer by a series of ports 10 and combines with the glowing gases, carbon, or smoke arising from the kiln. Above the arches 1 and 2 is placed a sheet-metal cylinder 11, lined with fire-brick 12. The interior of the lining is cylindrical at the top and thereafter is gradually narrowed downward in one direction, (see Fig. 4,) so that at the bottom it coincides with the slot 3 between the arches 1 and 2. I provide another series of air-ports 13, which are supplied with air from an encircling passage 14. The air is supplied to this passage by means of inlet-pipes 15, and this construction facilitates ventilation of the space 16, where the stokers of the fuel stand. In some cases

the air-chambers 8 and 14 may both be supplied with air under pressure.

I wish particularly to point out that only 55 limestone is fed into the top of the economizer and only fuel is fed through the openings 5. There is thus no combustion of fresh fuel in the economizer; but the limestone receives a preliminary heating and economizes 60 heat which would otherwise be wasted. The air entering at ports 10 combines with the smoke or incandescent carbon, and if carbon monoxide exists above the said ports it is converted into carbon dioxide by combination 65 with the air entering the ports 13.

I am aware that air has previously been supplied near the top of the column of mixed limestone and fuel, and I make no claim to that process; but with my invention the air is supplied 70 above the fuel-level, and the intense heat which usually exists at the constricted neck at the top of the kiln is not augmented at that point, and thus the destruction of the neck is lessened. With my invention the heat 75 is more gradually utilized, and I believe that perfect combustion of the gaseous and incandescent matters arising from the kiln is insured by my economizer.

What I claim as my invention, and desire 80 to protect by Letters Patent of the United States, is—

1. In an economizer for limekilns the combination of a receptacle for the limestone above the kiln, a pair of arches to support said receptacle, openings in said arches whereby fuel may be fed into the kiln, a series of ports adapted to supply air above the kiln, another series of ports at a higher level adapted to conduct a second supply of air above the first, 90 and means for supplying air to said ports, substantially as described.

2. In an economizer for limekilns the combination of a pair of arches spanning the top of the kiln and having air-inlets on their inner 95 faces, a receptacle for the raw stone supported by said arches in such manner that its contents may be heated by the products of combustion arising from said kiln, fuel-feed holes in said arches, an air-channel in the wall of 100 said receptacle above the top of said arches and ports leading from said air-channel to the interior of said receptacle and air-supply pipes leading from the outer portion of said

arches to the air-channel above mentioned whereby the latter may be supplied with air and the outer portions may be ventilated, substantially as described.

5 3. In an economizer for limekilns the combination of a double arch spanning the top of the said kiln and adapted to support a vessel to contain the limestone while receiving a preliminary heating, feed-holes for fuel in the 10 ends of said arches, a metal casing adjacent to the ends of said arches and air inlet and outlet ports communicating with the atmosphere and with the interior of the economizer, substantially as described.

4. In an economizer for limekilns the base 15 whereof consists of a pair of arches having fuel-feed holes in their end walls, the combination with said arches of metal sheaths forming air-chambers whereby the air may receive a preliminary heating before entering said 20 economizer, substantially as described.

In testimony whereof I have signed my name to this specification in the presence of two subscribing witnesses.

THOMAS RYAN.
